UNITED STATES PATENT OFFICE.

ADOLPHUS PETERSON, OF LANSDOWNE, PENNSYLVANIA.

PANORAMIC MYRIOSCOPE.

SPECIFICATION forming part of Letters Patent No. 661,725, dated November 13, 1900.

Application filed July 17, 1900. Serial No. 23,879. (No model.)

To all whom it may concern:

Be it known that I, ADOLPHUS PETERSON, a citizen of the United States, residing at Lansdowne, county of Delaware, and State of Pennsylvania, have invented a certain new and useful Improvement in Panoramic Myrioscopes, of which the following is a specification.

My invention relates to new and useful improvements in panoramic myrioscopes or exhibitors for displaying figured fabrics—such as carpets, wall-papers, and the like—and is designed to improve upon similar devices, for which patents of the United States were granted to me July 10, 1883, No. 280,855; July 15, 1898, No. 607,074; July 12, 1898, No. 607,073; June 28, 1898, No. 606,236, and June 28, 1898, No. 606,235.

The objects of my present invention are, first, to provide a complete self-sustaining collapsible device for obtaining both horizontal and oblique rereflecting effect, as well as an outside easel effect, without the aid of other support; second, to provide new means to avoid the open line of light in the reflection of the pattern at the bottom of the mirror-box; third, to provide an upward adjustment of the inner panel or bottom rest within guides in side bars forming parts of the top of stand, so that after the sample is resting in position on said bottom the open dark spaces between the four bottom edges of the mirror-box and the sample resting beneath on said panel are not rereflected; fourth, to provide a solid recess for a removable mirror-box on top of the said side bars, also to prevent it from moving forward, sidewise, or upward when lowered, and when samples are rolled under it arrange for its convenient transfer from one stand to another, thus making one mirror-box answer for several carpet and wall-paper displayers, or both, and, fifth, to provide new means to keep the mirror-box in true right-angled position for both horizontal and oblique display.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying draw-

ings, forming a part of this specification, in which—

Figure 1 is a perspective of my improved displaying apparatus, showing it adjusted for use; Fig. 2, a similar view showing the apparatus in its folded position; Fig. 3, a section in which the display-box is held in either a horizontal or oblique position, whether removably hinged or hooked, arranged to slide or roll outward or lift upward, the box and one of the sample-rolls being shown in dotted lines as turned down upon the frame; Fig. 4, a cross-section of the display-box, illustrating the manner of elevating the bottom so as to cause the sample to be bound tightly against the under edges of the sides of the box to shut off the reflection of open spaces or dark lines under these edges; Fig. 4^a, a plan view of the top of the frame or stand, showing the notches for guiding the movable bottom; Fig. 5, a side view of the mirror-box; Fig. 6, a detail view showing the manner of forming the exhibition-box, the sides being secured together by dovetail fittings; Fig. 7, an enlarged detail perspective showing one of the members by which the exhibition-box is secured upon the frame illustrated in Fig. 6, and Fig. 8 a similar view of the other member of these means.

In carrying out my invention I provide the side bars A, which rest upon the collapsible stand, consisting of the members B B and C C. The members B are removably hinged by means of spring-cotters a' to the side bars A at the point b, and the members B and C are hinged together at the point D in the same manner. The members B and C when in use are held in position by the folding strap E, which will hold the collapsible stand in position to be similar to that of an easel and prevent the spreading of the members B and C. The side members A are joined together at their ends by the end rails F. These end rails are L-shaped in cross-section, for the purpose hereinafter described. These side bars and end rails F will thus form a hollow frame, and the side rails A, being hinged at the point b to the collapsible stand, will assume a horizontal position when supported by the folding supports G.

H is the mirror-box, which is adapted to rest upon the hollow frame formed by the

side bars and the end rails F. This mirror-box H consists of the end pieces I I and the sides J J. The end pieces I have on their lower corners the extensions i. These extensions rest upon the side bars A, and so support the entire mirror-box. The end pieces I are removably hinged or held to the side bars A, the hinges being secured to the extensions i and to the side bars A. The side pieces J of the mirror-box are not hinged to the collapsible stand, but are hinged at the point j to the end pieces I. The side pieces J are secured to the end pieces at the opposite end to the hinges by means of the tongue J', which is formed on that end of the side pieces J fitting into the mortise I', which is formed in the edge of the end pieces I. This is clearly shown in Fig. 6, the four hooks J² serving to hold these pieces in place, thus forming a solid right-angled box. The mortised fittings also prevent the sides J from moving upward or out of angle when the mirror-box is lowered for oblique reflection, so as to avoid breakage of mirrors and an uneven continuous reflective effect.

The mirrors K are secured upon the inner surfaces of both the side pieces J and the end pieces I. A roller L is journaled in folding braces S, hinged to blocks T on the members B of the collapsible stand, and held in the required position by folding supports U and blocks T, and a roller M is journaled in the members C. The object of these rollers is that the material to be exhibited is rolled upon one of the rollers and after passing underneath the mirrors and being exhibited is rolled upon the other roller until the first-named roller is empty, when the operation can be reversed. The material N in passing from the roller L extends upward and passes over the friction-roller O, which is journaled between the side bars A, and then the angle formed by the end rails F. This material N then passes across and underneath the mirror-box H and passes over a friction-roller P, which is also journaled between the side bars A, and within the angle formed by the other end rail F, the material from there passing downward to the roller M. It will be observed that in arranging rollers L and M in this position suitable easel effects outside of the mirror-box are also provided. The object of the end rails F being formed in the shape of an angle is that the downwardly-extending lip f will prevent any light from entering the mirror-box between the lower edges of the end mirrors and the material to be exhibited. The bottom edge of the extending lip f is rounded. The excluding of this line of light is of great advantage in the proper exhibiting of goods, as it is obvious that if the light were allowed to enter it would be rereflected and stop the effect desired to be produced.

To form a support for the material while passing beneath the mirrors, I provide the bottom board Q, over which the material

passes. This bottom board Q is movable vertically and is guided by means of the tongues Q', which are adapted to ride up and down in the notches Q², formed in the side bars A. The center of this bottom board Q rests upon the cam R, which is secured upon the shaft R'. This shaft is journaled in suitable bearings formed upon the under side of the side bars A and is adapted to be revolved by the crank R². This cam when in the position shown in Fig. 3 will hold the bottom board tight against the lower edges of the mirror-box H, but when revolved half-way will allow the bottom board Q to drop a slight distance. The object of the movability of this bottom board Q is to do away with the reflection of the dark line caused by any space that might be left between the material and the lower edges of the mirror. I do not refer to the line of light as previously described, but rather to the dark line that would be reflected if there were a space between the material and the lower edges of the mirror-box. Of course the material could not be moved very readily if the bottom board was clamped tightly against the lower edges of the mirror-box, so I provide means (represented by the cam R) for lowering the bottom board when the material is to be moved, and when the desired pattern is underneath the mirror-box the bottom is then raised, thus forcing the material in close contact with the lower edges of the mirror-box. The said side bars A are higher than the inner panel or bottom board Q, and their inner sides serve as guides for the samples, said samples passing also under the side pieces of the mirror-box.

When desired to make a more extended easel effect of any pattern outside of the mirror-box, I provide at the lower ends of the members C of the collapsible stand the round spring-pegs C'. The material or sample belt can thus be unwound from the roll M and looped down over the pegs C', as shown in dotted lines in Fig. 3, thus giving an easel effect the entire length of members C C. When winding the samples on roller M, these spring-pegs C' move upward out of position.

If the mirror-box is in the position shown in Figs. 1 and 3, it is obvious that a customer would either stand or use a high chair in inspecting the samples. If it is desired, the mirror-box can be folded down upon the members B, as shown in dotted lines in Fig. 3. Thus a customer can while seated in an ordinary chair inspect the samples. This position of the mirror-box is also especially desirable when exhibiting patterns of wall-paper and the like, as this oblique position will more nearly resemble the effect of looking at the wall of a room. The machine will work just as well when the mirror-box is in an oblique position as when it is horizontal. To obtain this position in the mirror-box, it is merely necessary to bend the supports G outward, when the weight of the box itself will

hold it in this position. Under the friction-roller O, I provide in some cases an extra friction-roller, under which the material would roll when the mirror-box is in the oblique position.

When it is desired to fold the apparatus, the four hooks J² on the mirror-box are released, and the side pieces J are swung outward until they are in a straight line with the end pieces I. Then the end pieces I are folded inward until they lie flat against the side bars A. The side pieces J then can be folded back by means of the hinges j on top of the end pieces I, so that the pieces I and J will lie back to back, and two hooks from upper end piece I are fastened to eyes in lower end pieces I to keep the two sets in position. When folded the mirrors on the faces of the side pieces J being facing outward will then be exposed to view. Then the two supports G are bent outward, allowing the frame formed by the side bars A and the end rails F to swing upon the hinge b downward against the members B of the collapsible stand. Then by bending upward the supporting-strap E the members B and C of the collapsible stand can be brought together, when the whole apparatus will be folded in a very compact form and can then be packed away or placed in an upright slanting position against the wall, so as to utilize the mirrors K, which, as before stated, would be in view. Before folding it would be necessary to wind all the material upon the rollers M and let down the folding-supports U, holding the roller L. It will be observed that this roller L in being folded down is entirely out of the way of roller M and material wound thereon when the apparatus is collapsed.

In Figs. 1 and 2 is shown a top view of the angle-shaped end rails F and in Fig. 3 a sectional view. The upper end rail is made to fit flush with side bars A, as shown in Fig. 5, in case it is desired to slide the mirror-box off said side bars. In Fig. 5 are shown the extensions i, held on their inner sides and lower corners to side bars A. A piece of metal rounded at its projection and resembling the upper part of a hinge is set into said extensions the thickness of said pin projection. This projection rests in an open upward-slanting socket made to fit flush into side bars A, so that end pieces I have room to let down, and side pieces J will swing outward flush with top of side bars A. Both sets of these sockets being made to slant upward, the mirror-box is easily slid into and out of same and when lowered any side or upward movement prevented, the end rail F serving to stop any downward movement. This is an advantage where a merchant has a large number of carpet or wall-paper samples, or both, to show, for he needs then only have two or more sample-stands and one mirror-box, and when desired to show another set of samples the mirror-box is slid, rolled, or lifted to the other stand. For said pur-

pose I sometimes make two sample-stands into one device.

It will be observed that several of the improvements herein described can also be utilized when a non-folding stand and mirror-box is preferred—as, for instance, when floor-space is not limited or when my automatic arrangement for winding the samples is attached.

When showing a carpet-border, one of the side mirrors is left open, the border is placed lengthwise on top of the pattern at side of the open mirror, and the rereflected effect of a bordered hall is seen through the end mirrors. When showing a ceiling-paper with the wall-paper, the mirror-box being in oblique position, a sample thereof is made to cover lower end mirror, and the effect of same is seen through the upper end mirror and the general effect of both papers rereflected through the side mirrors.

Having thus fully described my invention, what I claim as new and useful is—

1. In a panoramic myrioscope or exhibitor, a collapsible mirror-box adapted to rest upon a self-sustaining stand, supports extending from the said self-sustaining stand and adapted to support the mirror-box in a horizontal position, means for folding said supports whereby the mirror-box is allowed to assume an oblique position, means for guiding the material to be exhibited beneath the mirror-box in both its horizontal and oblique position, two rolls upon which the material is wound and unwound, the entire combination making a complete self-sustaining collapsible device, substantially as shown and described.

2. In a device of the character described, a right-angled mirror-box adapted to rest on a stand, a vertically-moving bottom board arranged beneath the mirror-box guided in notches and resting on side bars of said stand over which the material to be exhibited is adapted to pass, means for raising and lowering the bottom board within said bars, friction-rollers over which the material to be exhibited is adapted to pass, two rolls upon which the material is wound and unwound, angle-pieces which serve as end rails for the stand, and also to prevent the light from entering between the bottom of the mirror-box and the material to be exhibited, substantially as shown and for the purpose specified.

3. In a device of the character described, a collapsible stand consisting of the upright members B and C, side bars A, and angle-shaped end rails F and collapsible mirror-box H which is hinged to the side bars A, a vertically-moving bottom board Q arranged beneath the mirror-box and adapted to be guided up and down by the grooves Q² in the side bars A, cam R, and shaft R' for raising and lowering this bottom board, guide-rolls O and P over which the material is adapted to pass, rolls L and M upon which the material to be exhibited is adapted to be wound

and unwound, folding supports G adapted to hold the mirror-box in a horizontal position, substantially as shown and described.

4. In a device of the character described, 5 a mirror-lined box consisting of two ends and two sides, one side being hinged to one end, the other side being hinged to the other end, tongues formed in the end of the side pieces opposite and adapted to fit in mortises formed 10 in one end of the end pieces so as to form a solid right-angled box, hooks for holding the members of the box in position, extensions formed upon the lower corners of the end pieces, said extensions adapted to rest upon 15 a stand, substantially as shown and described.

5. In a device of the character described, 20 a collapsible stand consisting of the upright members B and C hinged together, a folding strap adapted to limit the spreading of these 25 members, side bars A hinged to the member B, angle end rails F joining the side bars A, folding supports G adapted to hold the frame consisting of the side bars A and the end rails F in a horizontal position, a vertically-moving bottom board adapted to be guided in notches formed in the side bars A, means for raising and lowering this bottom board, 25 guide-rolls journaled in the side bars A and

adapted to lie within the angle of the end rails F, folding supports for roll L adapted to 30 fold downward and out of the way of roll M when members B and C are closed, a right-angled removable mirror-box having in extensions rounded L-shaped metal extensions held by slanting open sockets, substantially 35 as and for the purpose specified.

6. In a device of the character described, 40 a right-angled mirror-box adapted to rest on a stand, friction-rollers guiding the material beneath the mirror-box, two rolls upon which the material is wound and unwound, angle-shaped end rails serving as cross-braces to side bars of stand and coming flush to outer bottom edges of end pieces in the mirror-box and having a lip projecting below the upper 45 edge of the friction-roll to prevent the admission of light beneath the two bottom ends of the mirror-box, as specified.

In testimony whereof I have hereunto affixed my signature in the presence of two subscribing witnesses.

ADOLPHUS PETERSON.
